UNITED STATES PATENT OFFICE.

HERMAN UTSCH, OF LITTLE FALLS, MINNESOTA.

COPY-HOLDER.

1,009,455.

Specification of Letters Patent. Patented Nov. 21, 1911.

Application filed February 18, 1911. Serial No. 609,326.

To all whom it may concern:

Be it known that I, HERMAN UTSCH, a citizen of the United States, and a resident of Little Falls, county of Morrison, and State of Minnesota, have invented certain new and useful Improvements in Copy-Holders, of which the following is a specification.

My invention is an improvement in copy holders, and consists in certain novel constructions and combinations of parts herein-after described and claimed.

The object of the invention is to provide a simple, economical and easily operated device of the character specified, which may be easily applied to and detached from a typewriter carriage, and which will travel with the carriage, will advance the copy synchronously with the advancement of the writing paper, and wherein the indicator of the typewriter carries the indicator of the copy holder, so that the two indicators always indicate on the copy that portion of the one that corresponds to the same portion of the other.

Referring to the drawings forming a part hereof, Figure 1 is a perspective view of the improvement in place on a typewriter, Fig. 2 is a transverse vertical section of the improvement, Fig. 3 is a section on the line 3-3 of Fig. 2, Fig. 4 is a bottom plan view of the shield, Fig. 5 is an end view of the copy roll showing the supporting lugs, and Fig. 6 is a front view of Fig. 5.

The present embodiment of the invention is shown attached to the carriage 1 of a typewriter 2, and the device comprises a copy roll or platen 3, arranged directly above the platen 4 of the typewriter. The roll, is provided with a central shaft 5, whose ends extend beyond the roll, and one end of the shaft is provided with a turning knob 6.

A trough or shield 7 of sheet material is arranged beneath the roll 3, and the shaft 5 is journaled in bearing slots 8, in cross bars 9, which connect the side walls of the trough at each end thereof. The trough in cross section is approximately semicircular, and fits roughly the periphery of the roll 3.

The rear edge of the trough is flared outwardly and backwardly to form a guide 10 for the copy 11, and a plurality of spaced transverse slots or recesses 12 are provided in the bottom of the trough. A rod 13 is arranged between the rolls 3 and 4, and a

plurality of wheels or collars or sleeves 14 of rubber or other suitable material are secured on the rod at points corresponding to the slots 12, through which the collars or wheels project.

The rod 13 is journaled in arms 15, and the said arms extend forwardly to a connection with a rod 16 rigidly connected with the carriage 1 of the typewriter. Said bar 16 extends substantially parallel with the front bar 17 of the carriage, and slightly to the rear thereof, and the arms 15 are pivoted on the said rod.

The cross bars 9 before mentioned, are offset inwardly in front of the trough, and from thence extend forwardly as arms 18 to a connection with the rod 16. The front end of each arm is provided with a transverse groove 19, for receiving the rod 16, and a latch lever 20 is pivoted intermediate its ends between a pair of spaced lugs 21 on the bar near the groove 19.

The front end of the lever is also transversely grooved to receive the rod 16, and a spring 22 presses the latch lever toward the rod. The latch lever bar and spring form a sectional clamp or bearing for engaging the rod, and for detachably connecting the holder for swinging movement on the rod.

A spring 23 is arranged between each arm 18 and the adjacent arm 15 of the rod 13, and normally pulls the roll 3 toward the rod 13 and toward the platen roll 4. A rod 24 is arranged above the roll 3, and is provided at spaced intervals with sleeves or collars 25 of rubber or like material, which bear against the surface of the roll 3 and hold the copy firmly in place.

The ends of the rod 24 are bent forwardly and downwardly at 27, and each extremity is provided with an inwardly extending angular lug 28, which is journaled in an opening in the adjacent arm 18. A spring 29 is arranged between each portion 27 and the adjacent arm 18.

The upper part of each of the portions 27 is bent downwardly toward the top of the roll as shown at 26 in Fig. 1 to bring the collars 25 into contact with the copy roll.

The shaft 5 of the roll 3 is provided with a gear wheel 30, at one end, one preferably adjacent to the knob 6. A pinion 33 is secured to the rod 13 and meshes with the gear wheel 30, and the platen roll 4 of the typewriter is provided with a gear wheel 110

35, meshing with the pinion. It will be evident that when the platen roll is turned by the knob 6, that the rod 13 will be rotated in the opposite direction to the platen roll and will in turn rotate the copy roll in the same direction as the platen roll. The copy and the paper being written upon will thus move synchronously. The gear wheels 30 and 35 are of the same size as are 10 also the rolls 3 and 4, so that the copy moves at the same rate of speed as the paper being written upon.

The indicator for the copy consists of an arm 40, provided at one end with an upwardly extending angular portion 41, extended adjacent to the copy on the copy roll and at the other end the arm is hinged at 43 to one end of a clamp 42.

The clamp is provided with a pair of 20 blades or jaws 44 for engaging the indicator 45 of the typewriter, and the jaws are clamped on the indicator by a set screw 46. The indicator 41 is in alignment with the indicator 45, and hence indicates always 25 a point on the copy corresponding to the point indicated on the writing paper by the indicator 45.

The entire copy holder may be swung forwardly as indicated in dotted lines in Fig. 30 2. The arm 40 is first swung upwardly, after which the holder may be lifted. The writing paper passes between the platen roll 4 and the collar 14, and the arms 18 and arms 15 of the shaft 13 serve to guide the 35 paper in its movement.

The collars 25 of the rod 24 hold the copy in such position that it may be easily read by the operator, and when not in use the entire device may be removed, by releasing 40 the clamp 42, and the clamp formed by the arms 18 and latch lever 21. The arms 15 of the rod 13 may be pivoted directly to the arms 18 if desired.

It will be evident that the device is simple in construction and operation, is light 45 in weight, compact, and not liable to get out of order. The copy is held firmly, in the proper position for easy reading, and the place being copied is always indicated.

50 The roll 3 is held in the open bearings of the cross bars by means of hooks 46, each of which is pivoted to the adjacent cross bar at 47, and engages over the shaft to detachably hold the said shaft in place.

55 The trough or shield 7 is preferably provided with a scale 32 at the upper edge of the front thereof and the said scale corresponds with the scale on the typewriter.

As shown more especially in Fig. 1, a plurality of lugs 33^a are secured to the bottom of the trough, and depend therebelow, and each lug is provided in its free end with a curved recess 34 for engaging and resting upon the rod 13, before mentioned. The 65 said lugs are hinged to the trough so that

they may be turned up against the bottom of the trough or turned down as may be desired.

As shown in Fig. 6, a spring 48 is connected with the trough adjacent to each lug, and the end of the spring bears against an extension 49 on the lugs, the said extension being square in cross section so that whether the lug is turned up or down the spring will hold it in position. When the lug is turned down as shown in Fig. 1, the copy roll is held out of engagement with the collars 14 so that the said roll may be turned by and without interference from the said collars. When the said lugs are turned down, the gear wheel 30 is raised out of mesh with the pinion 33, and the copy holder may be operated by the knob 6, independent of the platen roll.

I claim:—

1. In combination with the carriage of a typewriter, a copy holder comprising a shaft, a roll on the shaft, a gear wheel secured to one end of the roll, a trough in which the roll is supported, said trough having spaced transverse slots in its bottom, a rod lying beneath the trough, an arm at each end of the rod in which the rod is journaled, a plurality of collars on the rod extending through the slots of the trough, a cross bar at each end of the trough, each bar having an open bearing for the shaft, a hook pivoted at one side of the bearing and engaging the shaft, the front ends of the cross bars extending forwardly from the trough, a clamp at the free end of each of the said ends for pivotally engaging the carriage of the typewriter, a gear wheel on the platen roll of the typewriter, and of the same diameter as the gear wheel on the copy roll, and a pinion on the rod meshing with both gear wheels.

2. In combination with a typewriter, a copy holder comprising a trough having its rear side flaring outwardly, and provided with transverse slots in its bottom, a roll journaled in the trough, arms extending forwardly from the trough, a clamp at the free end of each arm for pivotally engaging the carriage of the typewriter, a rod beneath the trough, collars on the rod extending through the slots, an arm at each end of the rod in which the rod is journaled, said arms being connected to the carriage, springs pressing the roll toward the rod, a driving connection between the copy roll and the platen of the typewriter for operating said rolls synchronously, a rod above the copy roll, collars or wheels on the rod, and springs pressing the rod toward the 115 roll.

3. A copy holder comprising a trough having transverse slots in its bottom and flaring outwardly at its rear end, a roll journaled in the trough, an arm extending 120

forwardly from each end of the trough, a clamp at the free end of each arm for pivotally engaging the typewriter carriage, a rod below the trough having collars extending through the slots, arms connected with the typewriter carriage in which the rod is journaled, springs pressing the trough toward the rod, and a driving connection between the platen roll of the typewriter and the copy roll for synchronously operating the said roll.

4. A copy holder comprising a trough having transverse slots in its bottom and flaring outwardly at its rear end, a roll journaled in the trough, an arm extending forwardly from each end of the trough, a clamp at the free end of each arm for pivotally engaging the typewriter carriage, springs pressing the roll downwardly, and a driving connection between the platen roll of the typewriter and the copy roll for synchronously operating the said roll.

5. A copy holder comprising a trough having transverse slots, a copy roll journaled in the trough, a rod below the trough, collars on the rod extending through the slots, springs for pressing the said roll toward the rod, and arms extending forwardly from the ends of the trough, and having means for detachably engaging a typewriter carriage.

6. In a copy holder, a roll, a pair of spaced arms between which the roll is journaled, said arms having means at their free ends for pivotally engaging a typewriter carriage to permit the holder to swing forwardly on the arms, and springs pressing the roll toward the rod.

7. In a copy holder, a copy roll, a trough

in which the roll is journaled, said trough having transverse slots in its bottom, a rod below the trough having annular collars extending through the slots into engagement with the roll, means for supporting the holder above the platen roll of a typewriter and lugs hinged to the trough and adapted to engage the rod to support the copy roll out of engagement with the collars, and means for holding the said lugs in position against the bottom of the trough or in extended position for engagement with the rod.

8. In a copy holder, a copy roll, a trough in which the roll is journaled, said trough having transverse slots in its bottom, a rod below the trough having annular collars extending through the slots into engagement with the roll, means for supporting the holder above the platen roll of a typewriter and lugs hinged to the trough and adapted to engage the rod to support the copy roll out of engagement with the collars.

9. In a copy holder, a copy roll, a trough in which the roll is journaled, said trough having openings in its bottom, a rod below the trough having collars in the openings, means for supporting the holder above the platen roll of a typewriter, a gear wheel on the copy roll, a pinion on the rod meshing therewith, and means on the trough for engaging the rod to support the trough with the gear wheel out of engagement with the pinion.
